RESETTING DEVICE FOR SWITCHES

John C. Millsap, Ashland, Oreg.

Application July 13, 1953, Serial No. 367,399

7 Claims. (Cl. 200—83)

1

This invention relates to switches and more particularly to a resetting device for a switch of the type adapted to automatically open a circuit when a particular condition exists.

Although not necessarily restricted thereto, the present invention will be described in connection with a safety switch of the type disclosed in my copending United States patent application Serial No. 278,333, filed March 25, 1952, now abandoned. In the copending application, a switch is disclosed which includes a fluid pressure operated diaphragm. The arrangement of the switch is such that when the fluid pressure in the line to which the switch is connected falls below a predetermined pressure, certain contacts open to break a motor circuit thereby stopping the pump to which the motor is connected.

The application above referred to also discloses manually resettable means for closing the contacts after the condition which causes the stoppage is corrected. However, after pressure is reestablished in the fluid line, it is necessary for the operator to manually release the resetting means so that the contacts are free to automatically open again if and when the pressure drops. In the event that the operator forgets to release the device, the switch is completely inoperative and will fail to perform its function.

It is therefore the main object of the present invention to provide a resetting device which automatically disengages when the switch is in its normal position, so that said switch is free to act when the predetermined event again takes place.

Another object of the invention is the provision of a resetting device which is economical and simple to construct and effective under all conditions.

Other objects and advantages will be seen from the following specification and from the drawings therein:

Fig. 1 is a vertical cross sectional view through a fluid pressure responsive switch showing the present invention.

Fig. 2 is a top plan view of the switch with the housing top removed.

Fig. 3 is a horizontal cross sectional view through the switch housing at a point under the switch arm showing the invention in an inoperative position.

Fig. 4 is a side elevational view of the switch housing showing the action of the weighted portion of the resetting means.

Fig. 5 is a cross sectional view through a switch housing showing a modified form of the invention.

Fig. 6 is a greatly enlarged, semischematic cross sectional view of the preferred form of resetting means showing the same in cooperation with the switch arm.

2

Fig. 7 is a view similar to Fig. 6 showing still another modified form of the invention.

The preferred form of the invention, illustrated in Figs. 1-4 and 6, is shown in use with a switch substantially similar to that disclosed in the above mentioned copending application.

In detail, the switch comprises an upright housing generally designated 1 which is provided at its lower side with an internally threaded hole 2 for receiving therein a pipe which, in turn, is connected to the pressure side of the pump that it is desired to control.

A diaphragm 3 is provided which is adapted to deflect upwardly when fluid pressure is applied to its lower side. On diaphragm 3 is a switch arm actuating member 4 which engages the underside of switch arm 5 and swings the latter upwardly when pressure is applied to the diaphragm 3.

Switch arm 5 is pivotally supported at one end on the housing 1 by means of a pair of downwardly projecting pivot knobs 6 and is provided at its other end with contacts 7 arranged on a bar 8 which, in turn, is urged upwardly at all times by a helical compression spring 9. The spring 9 surrounds a headed pin 10 which is fastened at its lower end to switch arm 5.

Stationarily secured on a fixed insulating bar 12 above the switch arm 5 are a pair of fixed contacts 13 which are adapted to be engaged by contacts 7 on the swingable switch arm 5 when the latter swings upwardly. Fixed contacts 13 are provided with binding posts 15 to which the wires 16 may be secured in the usual manner. When the device is used as a safety switch to prevent a motor driven pump from running dry, the fixed contacts 12 are in series with the motor circuit so as to start and stop said motor as required.

The switch arm 5 is urged downwardly at all times by a helical compression spring 17 which acts on said arm adjacent its pivoted end (Fig. 1).

At this point the general operation of the switch may be briefly described.

Upon fluid pressure being applied to the underside of diaphragm 3, the same deflects upwardly and swings the switch arm 5 clockwise about its pivots 6 so that moveable contacts 7 engage the fixed contacts 13 to close the circuit which includes said fixed contacts 13. As long as the pressure on diaphragm 3 does not drop below a predetermined pressure, the circuit remains energized. However, if the pressure drops, the diaphragm deflection is not sufficient to hold the switch arm up against the urging of spring 17 and said arm swings downwardly (counterclockwise) and the contacts 13, 17 open, stopping the motor, and preventing the pump from running dry.

When it is desired to again energize the motor it is necessary to manually close the contacts 13,

17 by swinging switch arm 5 upwardly. The engagement of contacts 13, 17 must be maintained until pressure is reestablished against diaphragm 3. Inasmuch as attainment of the proper pressure may take considerable time (especially if the pump must be primed) it is necessary to hold the contacts closed while the operator concerns himself with other matters.

The present invention provides a resetting means for achieving this result.

Extending transversely of the switch arm 5 and under the latter is a shaft 20 which is rotatably supported adjacent its opposite ends in the housing 1. As best seen in Fig. 3, the shaft 20 is provided, intermediate its ends, with a pair of radially outwardly extending projections 21 which are adapted to engage the switch arm 5 when swung counterclockwise from the position of Figs. 1, 3, 4. In addition, projections 21 positively swing switch arm 5 upwardly to the dotted line position of Fig. 1 so that contacts 7, 13 are engaged. It should be noted in this connection that the compression spring 9 permits the switch arm 5 to overtravel the point at which the contacts 7, 13 first engage, and this is desirable because the contacts 7, 13 are thus held together under yieldable pressure.

At one end of the shaft 20 and outside housing 1 the shaft 20 is provided with a relatively heavy eccentric portion 23 (Figs. 2, 3, 4, 6) which tends, at all times, to swing the shaft 20 clockwise as seen in Figs. 1, 4 and out of engagement with the switch arm 5. However, when the shaft 20 is rotated counterclockwise (Fig. 1) to close contacts 7, 13, it frictionally engages the switch arm 5 so as to hold the shaft 20 and arm 5 in the relative positions illustrated in full line in Fig. 6. In other words, the torque on shaft 20 exerted by weighted portion 23 is not normally sufficient to overcome the friction between projections 21 and switch arm 5 which virtually holds the shaft 20 and arm 5 in a locked position.

The upper, or operative position of projections 21 is preferably such that a line between the point of engagement between projections 21 and arm 5 and the center of rotation of shaft 20 makes an angle of slightly less than 90 degrees with the horizontal. If such angle were equal to or exceeded a right angle, there would be no tendency for the shaft to rotate clockwise under the torque imparted by weighted portion 23 unless the weight of said portion were extremely great and the disposition of the eccentric weight accurately taken into account.

To prevent excessive manual swinging of shaft 20, an additional projection 25 (Figs. 2, 3) is provided on said shaft that is adapted to engage a stop, such as the shank of screw 26 (Fig. 4), to limit the swing of said shaft so that projections 21 do not reach top dead center.

In operation, when it is desired to reset the switch after the same has opened, the operator swings the eccentric weighted portion 23 of shaft 20 upwardly from the full line position of Fig. 4 to the dotted line position. As best seen in Fig. 6, the projections 21 on shaft 20 are thus swung to raise switch arm 5 to closed position and hold it there by friction. The motor is thus energized and the pump operates to build up pressure against diaphragm 3.

However, after resetting the switch, the operator is free to clear away any obstructions in the suction line of the pump, prime the pump, or take whatever other action is required. When

working pressure is again reestablished against diaphragm 3, the member 4 engages switch arm 5 and swings the same further in a clockwise direction against the resistance of spring 9. Further upward swinging of switch arm 5 reduces or eliminates the frictional force existing between projections 21 and switch arm 5 (Fig. 6), thus permitting the shaft 20 to swing clockwise under the torque existing by virtue of the eccentric weighted portion 23.

If, for any reason, pressure is reduced below a predetermined minimum the switch arm 5 is free to swing downwardly to disengage contacts 7 and 13 and thus break the motor circuit.

A somewhat different form of the invention is shown in Fig. 5 wherein a switch arm 30 of a different type is adapted to swing about a pivot 31 for urging movable contacts 32 into engagement with fixed contacts 33. An arm engaging member 34 is adapted to swing the switch arm 30 counterclockwise for engaging contacts 32, 33. In this case the portion of switch arm 30 that is provided with contacts 32 is disposed vertically, but it will be understood that the general operation is the same.

Pivotedly secured to switch arm 30 is one end of an elongated link 35 which is provided with an upwardly opening notch 36. Link 35 is vertically slidable within a vertically extending slot 37 in the adjacent sidewall 38 of the switch housing and the notch 36 is adapted to receive the upper margin of slot 37 as seen in dotted line in Fig. 5.

When link 35 is in said dotted position and the contact points 32, 33 are in engagement, it will be apparent, upon upward deflection of the diaphragm that the frictional grip between notch 36 and the sidewall 38 of the housing will be reduced permitting link 35 to drop downwardly to its full line position.

As in the case of the previously described structure, the contacts 32, 33 will then be permitted to open when pressure is reduced and switch arm 30 swings clockwise.

It will be noted that the force of gravity is employed in the above described cases to return the resetting device to an inoperative position once the pressure has been reestablished.

The present invention also contemplates the use of a spring or the like to apply the unbalancing force as illustrated in Fig. 7.

The structure disclosed schematically in Fig. 7 is similar to that shown in Figs. 1-4 and 6 except that the switch arm 40 is provided with spring means for urging the same upwardly at all times to open the contacts. The shaft 41, corresponding to shaft 20 in Figs. 1-3 and 6 is swung downwardly into frictional engagement with switch arm 40 and is urged upwardly at all times by an extension spring 42 which may be secured to any convenient fixed structure 43.

Upon downward movement of switch arm 40 to reduce the friction between the same and shaft 41, the spring 42 pulls the shaft 41 clockwise into inoperative position and thus permits the switch arm 40 to move upwardly to open the contacts when the fluid pressure falls below the predetermined minimum.

The present invention should not be understood as being restricted by the above detailed description and by the embodiments shown in the drawings as these are merely illustrative. Various modifications will occur to those skilled in the art without departing from the scope of the following claims.

I claim:

1. In a switch, a member having a moveable electrical contact thereon adapted to engage a fixed contact upon movement of said member toward the latter, means for urging said member away from said fixed contact at all times for opening the circuit which includes said contacts, a resetting element for spacing said member a predetermined distance from a fixed point and releasably held in spacing position by friction, thereby engaging said contacts and closing said circuit, means for urging said element to a position out of frictional engagement at all times whereby said element moves to said position when said member is moved toward said fixed contact to reduce the friction of said frictional engagement.

2. In a switch, a member having a moveable contact thereon adapted to engage a fixed contact when said member is moved toward said contact to a closed position, means for urging said member to an open position at all times for disengaging said contacts to open the circuit which includes said contacts, a resetting element for holding said member in said closed position and moveable from an operative position in which said member is so held by friction to an inoperative position permitting said member to be moved to an open position by said means, means for urging said element to said inoperative position at all times against said friction whereby said element moves to said inoperative position when said member is moved toward said fixed contact to reduce said friction.

3. In a switch, a member having a moveable contact thereon adapted to engage a fixed contact when said member is moved toward said contact to a closed position, means for urging said member to an open position at all times for disengaging said contacts to open the circuit which includes said contacts, a resetting element for holding said member in said closed position and moveable from an operative position in which said member is so held by friction to an inoperative position permitting said member to be moved to an open position by said means, means for urging said element to said inoperative position at all times against said friction whereby said element moves to said inoperative position when said member is moved toward said fixed contact to reduce said friction, said last mentioned means comprising a weight carried by said element for unbalancing the latter when in said operative position.

4. In a switch, a member having a moveable contact thereon adapted to engage a fixed contact when said member is moved toward said contact to a closed position, means for urging said member to an open position at all times for disengaging said contacts to open the circuit which includes said contacts, a resetting element for holding said member in said closed position and moveable from an operative position in which said member is so held by friction to an inoperative position permitting said member to be moved to an open position by said means, means for urging said element to said inoperative position at all times against said friction whereby said element moves to said inoperative position when said member is moved toward said fixed contact to reduce said friction, said element being supported for swinging into frictional engagement with said member and for urging the

latter toward said fixed contact and to said closed position.

5. In a switch, a member having a moveable contact thereon adapted to engage a fixed contact when said member is moved toward said contact to a closed position, means for urging said member to an open position at all times for disengaging said contacts to open the circuit which includes said contacts, a resetting element for holding said member in said closed position and moveable from an operative position in which said member is so held by friction to an inoperative position permitting said member to be moved to an open position by said means, means for urging said element to said inoperative position at all times against said friction whereby said element moves to said inoperative position when said member is moved toward said fixed contact to reduce said friction, said element being pivotally secured at one end to said member and engageable with a fixed abutment at its opposite end.

6. In a switch, a member having a moveable contact adapted to engage a fixed contact when said member is moved toward said contact to a closed position, means for urging said member to an open position at all times for disengaging said contacts to open the circuit which includes said contacts, an element swingably supported at one end for engagement of its opposite end with said member for urging the latter to said closed position with said opposite end of said element in frictional engagement with said member, said element being formed with a weighted portion eccentric to said one end for urging said element away from said member against the resistance of the friction between said element and said member whereby said element swings away from said member by gravity when the latter is urged toward said fixed contact while in said closed position.

7. In a switch having a fixed contact and a moveable contact adapted to be engaged and disengaged for making and breaking a circuit which includes said contacts, a member supporting said moveable contact for movement between engaged and disengaged positions, a pressure actuated diaphragm connected with said member for moving it toward said fixed contact to make said circuit when a predetermined fluid pressure is applied to said diaphragm, an element swingably supported at one end for engagement of its opposite end with said member for urging the latter toward said fixed contact to an engaged position with said opposite end of said element in frictional engagement with said member, whereby said contacts are closed by said element when said fluid pressure is less than said predetermined amount, means for urging said element out of engagement with said member at all times against the force of friction between said element and said member whereby said element is released from said member when said fluid pressure exceeds said predetermined pressure.
